UNITED STATES PATENT OFFICE.

HEINRICH FELDHUS, OF HALLAM, NEBRASKA.

POWER-HAMMER.

SPECIFICATION forming part of Letters Patent No. 716,019, dated December 16, 1902.

Application filed May 8, 1902. Serial No. 105,783. (No model.)

To all whom it may concern:

Be it known that I, HEINRICH FELDHUS, a citizen of the United States, and a resident of Hallam, in the county of Lancaster and State 5 of Nebraska, have invented a new and Improved Power-Hammer, of which the following is a full, clear, and exact description.

The object of the invention is to provide a new and improved power-hammer which is 10 simple and durable in construction, very effective in operation, more especially designed for light work—such as hammering plowshares, plow-points, and other articles—and arranged to enable the operator to control the 15 hammer for the latter to strike quick sharp blows or slow light blows, according to the nature of the work under treatment.

The invention consists of novel features and parts and combinations of the same, as will 20 be more fully described hereinafter and then pointed out in the claims.

A practical embodiment of the invention is represented in the accompanying drawings, forming a part of this specification, in which 25 similar characters of reference indicate corresponding parts in all the views.

Figure 1 is a front elevation of the improvement. Fig. 2 is a side elevation of the same. Fig. 3 is an enlarged front elevation of part 30 of the frame. Fig. 4 is a transverse section of the same. Fig. 5 is a sectional plan view of the same on the line 5 5 of Fig. 3. Fig. 6 is a perspective view of part of one of the base I-beams. Fig. 7 is a similar view of a portion 35 of one of the upright I-beams, and Fig. 8 is a sectional plan view of the improvement on the line 8 8 of Fig. 2.

The frame of the power-hammer is set on a suitable foundation A and consists, essentially, of a plurality of base I-beams B, B', and B², spaced apart and receiving between them, at the rear ends, the two upright I-beams C C', as plainly indicated in the drawings, the base and upright I-beams being fastened together by transversely - extending bolts D, and a bolt D' also connects the front ends of the base I-beams B B' B² with each other. A bolt E connects the upper ends of the upright I-beams C C' with each other. 45 (See Fig. 2.) The top and bottom flanges of the middle base I-beam B' are formed with notches B³, (see Fig. 6,) and similar notches

are formed in the top and bottom inner flanges of the outer base I-beams B B² and the said notches are adapted to be engaged 55 by corresponding notches C², formed in the flanges of the upright I-beams C C', so as to interlock the base and upright I-beams with each other. By this arrangement the beams forming the frame are prevented from shifting out of position relative one to the other, and thus produce a very strong durable frame.

On the front top portion of the base I-beams B B' B² rests the base F' of an anvil-block F, carrying a suitable anvil F², and the front end 60 of the base F' of the anvil-block is engaged by a transverse bar G, connected by bolts G' with the foundation A, so as to securely hold the anvil-block F in position on the base-beams and to assist in holding the frame in 65 position on the foundation. The rear end of the base F' is engaged by bolts G², (see Figs. 1 and 2,) extending downwardly between the base I-beams B B' and B' B² to engage clamping-plates G³, abutting against the under side 70 of the opposite flanges of the said base I-beams, as will be readily understood by reference to Fig. 1. The rear ends of the base I-beams B, B', and B² are engaged on top by a transverse bar G⁴ and connected by bolts 75 G⁵ with the foundation A to securely hold the rear portion of the frame in position on the said foundation. Clamping-plates E' and E² engage the front and rear faces of the upright I-beams C C', as illustrated in Fig. 2, 80 and the said clamping-plates are engaged by a bolt E³ to hold the plates in position and to assist in binding the upright beams in place.

A hammer H reciprocates over the anvil F² and is dovetailed in a dovetail formed in the 85 under side of the cross-head H' and is secured in place therein by a set-screw H², as indicated in Figs. 1 and 2. The cross-head H' is mounted to slide vertically in guide-plates H³, (see Figs. 1, 2, and 8,) fastened by 90 bolts I to channel-irons I', bolted or otherwise fastened to the front flanges of the upright I-beams C C'. The bolts I extend through elongated slots in the guide-plates H³, and the said bolts also engage angle-irons I² to fasten 95 the latter to the front flanges of the channel-irons I', and the said angle-irons I² are provided with bolts I³, engaging the outer edges of the guide-plates H³ to adjust the latter to-

ward each other to take up all wear between the cross-head H' and its guide-plates H³. The channel-irons I' are connected with each other by stay-bolts I⁴ (see Figs. 2 and 8) to strengthen the channel-irons.

The sides of the cross-head H' are provided with lugs H⁴, on which are fulcrumed links J, extending outwardly and pivotally connected at their outer ends with the free ends 10 of a leaf-spring K, connected at its middle portion with one end of a pitman L, engaging at its other end the wrist-pin N' of a crank-disk N, secured on the forward end of the main shaft O, journaled in suitable bearings 15 P P', bolted to the upper ends of the upright I-beams C C' at the front and rear faces thereof, so as to strengthen the frame of the power-hammer. On the shaft O is mounted loosely a driven pulley Q, adapted to be engaged by 20 a friction-clutch R of any approved construction and mounted to slide on and secured to the main shaft O, so that when the friction-clutch R engages the clutch member on the pulley Q then the shaft O is rotated to cause the latter to impart a reciprocating motion to 25 the cross-head H' and the hammer H by the action of the crank-disk N, pitman L, leaf-spring K, and links J, fulcrumed on the said cross-head. The shifting lever R' for the 30 friction-clutch R is connected by a link S with a bell-crank lever S', fulcrumed on the upright beams C C', and pivotally connected by links S² with the treadle S³, fulcrumed on links S⁴, pivoted to the upright beams C C', 35 as plainly indicated in the drawings, the said treadle S³ extending to the front of the foundation A, so as to be within convenient reach of the operator's foot. Now when the operator presses the treadle S³ then the above-described connection with the shifting lever R' imparts movement to the latter to move the friction-clutch R in frictional engagement with the driven pulley Q to cause rotation of the shaft O for the purpose previously 40 stated. Now by the operator pressing the treadle S³ with more or less force the friction-clutch R is thrown in more or less frictional contact with the driven pulley Q to cause a more or less positive driving of the 45 shaft O to regulate the force of the blow of the hammer H on the article under treatment and held on the anvil F².

The wrist-pin N', previously mentioned, is 50 preferably readily adjustable on the crank-disk N, so as to permit of varying the throw

of the crank N and the stroke of the cross-head H' and hammer H to adapt the hammer for larger or smaller work.

The entire machine is very simple and durable in construction, not liable to easily get 60 out of order, and enables the operator to control the hammer for the latter to strike quick sharp blows or slow light blows, according to the nature of the work under treatment.

Having thus described my invention, I claim as new and desire to secure by Letters Patent—

1. A power-hammer having a frame, comprising flanged and spaced horizontal base-beams, flanged and spaced upright beams between the base-beams, the flanges of the beams being formed with interlocking notches, and bolts engaging the sets of beams, to fasten the same in position, as set 70 forth.

2. A power-hammer having a frame, comprising a plurality of horizontal spaced I-beams for forming the base of the frame, the I-beams having notches in opposite top and bottom flanges, spaced upright I-beams extending between adjacent base I-beams and having notches to engage the notches in the base-beams, and bolts for fastening the base and upright beams together, as set forth.

3. A power-hammer having a pair of spaced upright I-beams, channel-irons secured to the front flanges of the upright I-beams, cross-head guide-plates on the said channel-irons, angle-irons on the said channel-irons, bolts for securing the guide-plates and angle-irons to the channel-irons, and set-screws in the said angle-irons, to engage and adjust the said guide-plates, as set forth.

4. In a power-hammer, the combination 95 with a supporting-frame provided with forwardly-projecting lugs, of cross-head guide-plates provided with slots, bolts passing through the frame and slots of the guide-plates, and bolts carried by the lugs of the 100 frame and engaging the outer edges of the guide-plates, for adjusting the same, as set forth.

In testimony whereof I have signed my name to this specification in the presence of 105 two subscribing witnesses.

HEINRICH FELDHUS.
